UNITED STATES PATENT OFFICE

JACOB E. NEAHR, OF HARTSDALE, NEW YORK

MATCH SAFE

Application filed April 7, 1925. Serial No. 21,265.

This invention relates to improvements in ash-receivers, including features of construction of the body of the ash-receiver and also improvements in cigar or cigarette extinguishers and means for attaching the same 5 to the ash-receiver.

Preferably the ash-receiver is hollow walled, being inexpensively formed from thin sheet-metal by spinning or forming a bowl-portion, and then spinning or drawing the metal down around the bowl-portion to form 10 a skirt, the skirt extending below the bowl and its lower edge being spun or formed inwardly to make an annular base-portion. This base-portion preferably has an upturned inner edge which co-operates with the under side of said bowl to form a clip or depository for a match-book.

Upon the ash-receiver is a cigar-rest, which 20 is pivotally supported, and which co-operates with a support or shelf therebeneath to form cigar or cigarette extinguishing jaws. This combined cigar holder and extinguisher is provided upon a clip which catches over the 25 brim of said ash-bowl, and which has an extension or claw which extends down alongside the skirt or outer wall of the ash-receiver and hooks into a crevice formed in the bottom of said ash-receiver.

Other features and advantages will herein-after appear.

In the accompanying drawings,

Figure 1 is a sectional elevation of the improved ash-receiver, provided with a combined cigar rest and extinguisher; a book of matches being shown tucked into the clip or repository under the bowl of the ash-receiver.

Figure 2 is a part-sectional bottom view of the ash-receiver.

Figure 3 is a plan of the same.

Figure 4 is a sectional elevation illustrating the operation of pinching and extinguishing a cigarette.

Figure 5 is a sectional elevation showing 45 the cigar-extinguisher detached from the ash-receiver.

The ash-receiver is preferably made of spinning brass or other thin sheet-metal, and may be inexpensively made by first spinning 50 the bowl-portion 10, and then spinning or

drawing down the skirt or outer wall 11, thus forming a double wall. The bead where the inner wall joints the outer wall forms the brim 12 of the ash-receiver. The outer wall or skirt-portion 11 of the double wall may 55 flare downwardly and outwardly; and its bottom may be still more outwardly flaring at 13 to form a large bottom bead-portion; this bead-portion merging into an inwardly and upwardly turned base-portion or flange 14, which rests upon the table.

This base flange 14 may at its inner part be turned upwardly at 15, its upper edge 16 being spaced only a little below the bottom 17 of the ash-bowl, to leave only sufficient room 60 for inserting therebetween the thin end 18 of a book of matches 19, to hold the same against accidental displacement; the bottom 17 of the ash-receiver bowl being sufficiently spaced above the table 20 to accommodate the thick 65 end 21 of the match-book. The ash-receiver may be picked up and carried about without danger of the match-book falling out; and by turning the ash-receiver over the match-book may be rendered readily accessible, as 70 at Figure 2, and withdrawn for use. It will be seen that the unsightly match-book is completely covered by the small, inexpensive and ornamental ash-receiver structure.

The ash-receiver is provided with a cigar-rest 22 which is pivoted at 23 between its ends, the portion thereof on the inner side of the pivot being utilized for a pinching jaw, and the portion on the outer side of the pivot being used as a depressible finger-piece for 85 opening the jaw. It will be seen that the thumb or finger may rest along the hollow of the cigar-rest, for both opening and closing the same. A shelf 24 beneath the inner arm of the cigar-rest supports the lighted cigarette 25, Figure 4, the members 22 and 24 forming jaws between which the same is pinched.

For thus using the cigar-rest for this double purpose, economy is effected in manufacture, 90 and simplicity of construction is attained, as well as simplicity and convenience of operation. Moreover, the device conduces to the attractiveness and salability of the entire article.

The introduction of a lighted cigar has the effect of pushing along the ashes deposited upon the cover by the previous cigar. Between the tip of the lower jaw or shelf 24 and pivot 23 may be provided an opening 26 in the shelf, thereby permitting the deposited ashes, as they are thus pushed back from time to time, to fall through into the ash-receptacle 10.

10 In forming the hole 26 in the shelf, the material of said shelf is bent upwardly, forming a stop 27 immediately in rear of the hole, this stop limiting the inward thrust of the cigarette, as seen at Figure 4.

15 As a further improvement, each combined cigar tray and extinguisher may be provided with side flanges or cheeks 28 pendent from the sides of the cigar rest or tray 22 and forming a box or pocket into which the burning 20 end of the cigar or cigarette is thrust. Hence when the ashes are pinched off, they remain confined within this pocket, and are not scattered, but may be pushed along by subsequently inserted cigars, until they fall 25 through the opening 26. These cheeks or side flanges 28 preferably extend down below shelf 24. They lend a pleasing appearance of simplicity and solidity to the structure, and also serve as weights to hold the extinguisher 30 down in normal position.

For simplicity and durability, the cigar-rest may be pivoted without the use of a separate pintle. Gudgeons 29 are pressed inwardly in the metal of the cheeks 28, and fit 35 into cups 30, Figure 5, which are pressed in ears 31 of shelf 24. The gudgeons are so short that the parts may be sprung together, and will remain permanently jointed.

The combined cigar rest and extinguisher 20 may be detachably secured on the ash-receiver in an inconspicuous, inexpensive and simple manner by means of a strap 32, which forms a continuation of the shelf 24 being bent downwardly therefrom and conforming to 45 the curvature of the ash-receiver. The strap terminates in a hook 33, which catches in an annular groove or gutter 34 formed in the under side of bottom 14, just within the periphery of the bead 13; this groove 34 preferably ex- 50 tends all the way around the base, so that the cigar-extinguisher may be attached at any point.

This clip comprises not only the lower 55 hook 33, but also an upper hook, in the form of fixed cheeks 35, just inside of the movable cheeks 28; said hook 35 catching over the brim 12 of the ash-receiver and extending down within the same. The strap is sufficiently yieldable to permit the bottom hook 60 to be sprung into and out of holding position.

In the floor 14 of the ash-receiver base are formed holes 36, through which may drain water used in cleaning out the space above 65 said floor.

The body of the ash-receiver may, if de-

sired, be of glass or ceramic ware or other material, and to the bottom there may be applied an annular floor or base, having an upwardly and inwardly turned edge to co-operate with the bottom of the bowl to form a clip 70 for the match-book; and such base may have the drainage holes 36.

Variations may be resorted to within the scope of the invention, and portions of the improvements may be used without others.

Having thus described my invention, I claim:

1. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette.

2. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette, said clip having means to hook over the top and bottom of the ash-receiver.

3. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette, said clip comprising a strap extending down the side of the ash-receiver and hooking over the top and bottom thereof, the bottom of said ash-receiver having an annular groove to receive the lower hook.

4. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette, the cigar-holder comprising side 100 walls or plates between which said shelf is arranged.

5. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette, said shelf having an opening through which the ashes may drop into the 110 ash-receiver.

6. An ash-receiver, a cigar-holder and a clip to which said cigar-holder is pivoted and whereby it is held upon said ash-receiver, said clip having a cigar or cigarette shelf or support under said cigar-holder to co-operate therewith to pinch and extinguish a cigar or cigarette, the cigar-holder comprising side walls or plates between which said shelf is arranged, said shelf having an opening through 120

which the ashes may drop into the ash-receiver and a cigar-stop back of said opening.

7. An ash-receiver, a cigar-holder having cheeks and a clip to which said cigar-holder is pivoted and whereby it is held upon said ash-receiver, said clip having a cigar or cigarette shelf or support under said cigar-holder to co-operate therewith to pinch and extinguish a cigar or cigarette, said clip having means to hook over the top and bottom of the ash-receiver, the upper hook in the form of plates confined between the cheeks on said cigar-holder.

8. A device for attachment to a cigar-extinguisher, comprising a shelf having supporting means to catch over the top and bottom of the cigar-extinguisher and provided with an ash-remover, said remover including a support upon said shelf and a co-operating pinching device pivoted upon said shelf.

9. A device for attachment to an ash-receiver, comprising a shelf having supporting means to catch over the top and bottom of the ash-receiver and provided with a cigar-extinguisher including a support upon said shelf and a co-operating pinching device pivoted upon said shelf, and comprising side walls or plates between which said support is arranged.

10. A device for attachment to an ash-receiver, comprising a shelf having supporting means to catch over the top and bottom of the ash-receiver and provided with a cigar-extinguisher including a support upon said shelf and a co-operating pinching device pivoted upon said shelf, and comprising side walls or plates between which said support is arranged, said pivoted device comprising a finger-piece having a depression to serve as a cigar-rest.

11. As a new article of manufacture, a metal clip having means to catch over the top and bottom of an ash-receiver and carrying a support to rest against the inner wall of the ash-receiver, and a cigar-pincher pivoted upon said support.

12. An ash-receiver, a combined cigar rest and extinguisher, and a clip holding the combined rest and extinguisher detachably upon the ash-receiver.

13. An ash-receiver formed from thin sheet-metal and including a bowl-portion which at its brim is turned downwardly to form a skirt extending below the bowl, said skirt being turned inwardly to form an annular base-portion, said base-portion having an upturned inner edge co-operating with the under side of the bowl to form a clip for a match-book.

14. An ash-receiver comprising a bowl and an annular base upon which the bowl is supported, said base beneath the bowl and co-operating with the bottom of the bowl to form a clip for a match-book.

15. An ash-receiver comprising a bowl and

an annular base upon which the bowl is supported, said base beneath the bowl and co-operating with the bottom of the bowl to form a clip for a match-book, said base having a crevice or groove extending around its under portion, a clip hooked into said crevice and hooking over the brim of the bowl, and a shelf formed upon said clip to co-operate with a pivoted cigar-rest to form an extinguisher for cigars or cigarettes.
